UNITED STATES PATENT OFFICE.

HARRY V. BALL, OF CONCORD, MASSACHUSETTS, ASSIGNOR TO R. HOE & CO., INC., OF NEW YORK, N. Y., A CORPORATION OF NEW YORK.

ADJUSTABLE INK-PUMP RAIL.

Application filed January 14, 1926. Serial No. 81,190.

This invention relates to certain improvements in inking mechanism for printing machines, and is designed particularly for use with the type of mechanism shown in United States Patents No. 1,214,856, dated February 6, 1917, and No. 1,311,198, dated July 29, 1919, both to B. C. White.

In the type of inking mechanism shown in these patents, the ink is supplied through a series of separate conduits, one conduit being provided for each column or other desired section of the form to be inked, this ink being delivered under pressure in the desired quantity by a plurality of independent pressure devices, such as pumps, one of these pressure devices being provided for each conduit so that the quantity of ink delivered to each column or section may be varied as desired.

20 In producing certain products, as, for instance, an illustrated page or a page the printed matter of which is chiefly illustration, it may be desirable that the ink supplied to such page be greater or less than the ink supplied to other parts of the form or forms, and it is desirable for quick and speedy adjustment that the ink supply for such a page may be readily and quickly regulated.

30 It is a special object of the invention to provide a construction by which the thickness of the ink film from the conduits supplying a page may be increased or decreased throughout the whole width of the page, this adjustment being such that it can be effected by a single adjusting movement, so that a quick and effective ink adjustment can be made.

A further object of the invention is to 40 produce such a construction in which the parts are readily accessible and in which the adjustment can be effected from a conveniently central point in the machine.

With these and other objects not specifically referred to, the invention consists in certain novel parts, arrangements, and combinations which will be fully described in the accompanying drawings and the novel features pointed out in the claims hereunto 50 annexed.

The accompanying drawings show one construction for effecting the objects of the invention and in these drawings,—

Figure 1 is a diagrammatic end view, 55 partly broken away and partly in section,

showing a printing couple and the improved inking mechanism and its preferred position with respect to the couple;

Figure 2 is an enlarged cross-sectional view showing the mechanism for effecting 60 the desired adjustment;

Figure 3 is a rear view of the inking mechanism, the view being taken in the direction of arrow 3 of Fig. 1;

Figure 4 is a plan view of a portion of the 65 ink distributing mechanism, certain parts being broken away and certain parts being in section;

Figure 5 is a detail view, the view being taken in the direction of arrow 5 of Fig. 70 2;

Figure 6 is a detail side view of one of the adjusting members, and

Figure 7 is a detail face view of the construction shown in Fig. 6. 75

Referring now to these drawings, one printing couple is diagrammatically shown including a form cylinder 1 and an impression cylinder 2 printing on a web W, these cylinders being suitably mounted in side 80 frames 3.

The particular machine selected to illustrate the invention is a rotary machine in which both members of the printing couple are cylinders, but it will be understood that 85 the invention as to certain of its features will be useful in other types of machines and in machines in which both elements of the couple are not cylinders, and it will also be understood that the inking mechanism 90 is provided as necessary or desirable in multi-couple machines.

In the particular construction illustrated, the form cylinder 1 is inked from a pair of distributing rolls 4, 5, which take ink from a drum 6 to which ink is supplied from a roll 7 which receives ink from the inking mechanism indicated generally by the numeral 8. 95

In the particular construction shown, the forms to be inked are four plates arranged widthwise of the cylinder 1, each plate being eight columns wide. Ink is supplied from the inking mechanism 8, under pressure, by suitable pumps, not shown, through 100 a plurality of conduits, one of these conduits being provided for each column or other section of the form, thirty-two of these conduits, marked 9, being provided in the present instance, corresponding to the thirty-two 110

columns of the page to be printed. These conduits are conveniently supported in a recess 10 formed in a frame or rail 11, and generally termed the ink rail, and each conduit delivers to a distributing opening or nozzle 13 which supplies a column or other desired section of the form. These nozzles or openings are separated from each other by suitable partitions 14, see Fig. 4, and deliver ink to the roll 7, before referred to, these nozzles lying closely adjacent the roll.

The ink rail is formed with a downwardly extending portion 15, below the nozzles, which is curved to approximately the curve 15 of the distributor roll 7 and lies closely adjacent thereto, this portion of the rail acting to regulate the ink delivered to the roll.

In accordance with the invention, means are provided for manipulating the rail so that the distance between the distributing face 16 of the part 15 and the roll may be varied, so as to permit an ink film of different degrees of thickness to be taken away by the distributor roll. These means are such that the ink distributed by a plurality of the conduits may be simultaneously adjusted without effecting that distributed from other conduits, and the means for effecting this will be conveniently arranged for the operator, as by locating the adjusting mechanism at one side of the machine so that any desired adjustment can be made from one point. While the specific construction for effecting this may be varied with considerable limits, that illustrated is a convenient one. As shown, the distributing part of the ink rail is divided into a plurality of sections which are mounted so as to be movable independently of each other toward and from the distributing roll. While the number of conduits carried by each section may vary as desired, in the particular construction shown there are four such sections, marked 17, 18, 19 and 20, each one of these sections carrying eight distributing nozzles 13 for eight columns or sections of the form, such number in the present instance making up a one page width, so that by adjusting one of these sections the ink supply to any particular page is regulated as may be desired. It will be understood, however, that the rail may be divided into as many sections as may be necessary or desirable, an operating mechanism for each of the sections being provided as hereinafter referred to.

In the particular construction illustrated, these sections which form part of the ink rail are made independent of each other and independent of the rail and have a sliding movement relatively to the main part of the rail 11, before referred to, and toward and from the distributing roll 7. In the particular construction shown, therefore, these sections 17-20 are provided with a rearward extension 21 which has a sliding movement

on a projecting portion 22 of the rail, the sections being guided in their movement on suitable guides 23 extending into the rail 11 and the downwardly extending distributing portion 15, before referred to. These sections are given a sliding movement in any suitable manner.

In the particular construction shown, this is effected by certain rod and gear constructions, the operating mechanism for which may be centrally located at a convenient point at one side of the machine, an operating mechanism for each section being provided. As shown, each section has secured thereto a bracket 24 provided with a leg 25 which receives the end 26 of a threaded adjusting screw 27 which is tapped into a socket in the extension 22 of the fixed part of the rail 11. This threaded screw 27 carries a gear 28 which meshes with a gear 29 on one end of a shaft 30 mounted in suitable bearings 31 on the rail 11, before referred to. The outer end of this shaft 30 is provided with a gear 32 which meshes with a gear 33 on the end of a rod 34 which extends widthwise of the machine beyond the rail, as shown in Fig. 3, this rod being supported in suitable bearings 35 and having on one end an operating wheel 36. It will be seen that by rotating the operating wheel 36 the section controlled thereby is given a movement toward and from the distributor 7, thus adjusting the width of the ink gap between the distributor face 15 of the ink rail and the distributor roll 7, so that more or less ink is taken away and delivered by the distributor roll. With this construction it follows that the adjustment can be made without changing or adjusting the pumps, it being understood that the conduits 9 are sufficiently flexible to permit this adjusting movement without injury thereto. As the amount of this adjusting movement is very slight, a speedy and effective adjustment for the ink widthwise of the distributor roll 7 is, therefore provided, and one which can be conveniently made from a central point of the machine.

Cooperating with the ink rail is a cover plate or cap 37 which covers the nozzles 13. To permit ready access to the conduits, this cap or plate is arranged so it can be readily removed, and in the particular construction shown the cap or plate is hinged at 38 to the part 21 of the sections 17-20 and is held in closed position by springs 39. The various parts of the inking mechanism may be supported in the side frames 3, before referred to, and the pumps may be conveniently mounted in the fountain casing, indicated generally by the numeral 8.

While the invention has been shown and described in its preferred form, it will be understood that certain changes and variations may be made in the specific construc-

tion described and in the arrangement of the ink rail without departing from the invention as defined in the claims hereunto appended.

5. What I claim is:

1. In an inking mechanism, a distributing member, feeding openings through which ink is delivered to the member, one of these openings being provided for each column or section of the form, and means for effecting a relative adjustment of a plurality of these feeding openings with respect to the distributing member without affecting the position of other feeding openings with respect to the member for regulating the thickness of the ink film supplied from the openings.

2. In an inking mechanism, a distributing member, feeding openings through which ink is delivered to the distributor, a sectional support in which the openings are formed, and means for effecting an adjustment of a section of the support to and from the distributor without affecting the position of the other sections.

3. In an inking mechanism, a distributing member, feeding openings through which ink is delivered, a support in which the openings are located, said support being divided into sections, each section having a plurality of openings, and means for effecting an adjustment of a section to and from the distributor without affecting the position of other sections.

35. 4. In an inking mechanism, a distributing member, feeding conduits, one for each column or section of the form, a sectional ink rail to which the conduits deliver, and means for adjusting the rail sections independently of each other to and from the distributor.

40. 5. In an inking mechanism, an ink rail having a plurality of sections, feeding openings in each section, a member to which ink is delivered from the openings, and means

for adjusting the rail sections independently 45 to and from the member.

6. In an inking mechanism, an ink rail having a plurality of sections, feeding openings in each section, a member to which ink is delivered from the openings, and means 50 located at a common point for adjusting the rail section to and from the member.

7. In an inking mechanism, an ink rail, feeding conduits supported by the rail, a sectional feeding member to which the conduits deliver having feeding openings, and means for adjusting the sections on the rail to vary the position of the feeding openings with respect to each other.

8. In an inking mechanism, an ink rail, 60 feeding conduits supported by the rail, a sectional feeding member to which the conduits deliver having feeding openings, and means located at a common point for adjusting the sections on the rail to vary the 65 position of the feeding openings with respect to each other.

9. In an inking mechanism, an ink rail, 70 feeding conduits supported by the rail, a sectional feeding member to which the conduits deliver, a plurality of feeding openings in each section, and means for adjusting the sections on the rail to vary the position of the feeding openings with respect to each other.

10. In an inking mechanism, a distributing member, feeding openings through which ink is delivered to the distributor, a sectional support in which the openings are formed having a relatively wide distributing face 80 curved to correspond with the periphery of the distributor, and means for effecting an adjustment of a section of the support to and from the distributor without affecting the position of the other sections.

In testimony whereof, I have hereunto set my hand.

HARRY V. BALL.
